UNITED STATES PATENT OFFICE.

THOMAS B. JEFFERY, OF KENOSHA, WISCONSIN; KATE E. JEFFERY, CHARLES T. JEFFERY, AND HAROLD W. JEFFERY EXECUTORS OF SAID THOMAS B. JEFFERY, DECEASED.

AUTOMOBILE COOLING SYSTEM.

1,100,888.

Specification of Letters Patent. Patented June 23, 1914.

Application filed February 23, 1904. Serial No. 194,762.

To all whom it may concern:

Be it known that I, THOMAS B. JEFFERY, a citizen of the United States, residing at Kenosha, county of Kenosha, State of Wisconsin, have invented a certain new and useful Improvement in Automobile Cooling Systems, and declare the following to be a full, clear, and exact description of the same, such as will enable others skilled in the art 5 to which it pertains to make and use the same, reference being had to the accompanying drawings, which form a part of this specification.

My invention relates in general to systems 15 for dissipating the heat generated by explosive engines, and particularly to circulating fluid systems especially designed for cooling the cylinder of an automobile. In automobile cooling systems in which a circulating fluid is used to absorb the heat 20 from the cylinder it is customary to provide a radiator preferably located at the front of the automobile through which the heated fluid from the water jacket around the cylinder passes and is there cooled by radiation. Prior to my invention, so far as I am aware, 25 the circulation of the cooling fluid in such systems has been produced by a pump the operation of which draws the heated fluid 30 from the water jacket around the cylinder and forces it through the radiator, after which the cooled fluid is returned to the water jacket by the forced circulation produced by the pump. The employment of a 35 pump for inducing circulation is objectionable not only because it adds to the complication of the automobile mechanism, but primarily because when for any reason the pump ceases to operate, the circulation 40 continues, resulting in the cylinder becoming overheated and the piston sticking therein.

The primary object of my invention is to 45 provide a fluid cooling system for automobile engines in which the usual pump for producing circulation between the water jacket around the cylinder and the radiator at the front of the automobile, is dispensed with, and the circulation produced entirely 50 by the rising of the fluid as it is heated in the water jacket and the falling of the fluid as it is cooled in the radiator.

A further object of my invention is to provide a cooling system for automobile engines which will be simple in construction, inexpensive in manufacture, and efficient in use. 55

My invention, generally described, consists in a radiator supported at the front of an automobile having a partition therein, a water jacket surrounding the engine cylinder, 60 a conduit extending from the top of the jacket to the radiator at one side of the partition, a return pipe extending from the radiator at the other side of the partition and communicating with the bottom of the water 65 jacket.

My invention will be more fully described hereinafter with reference to the accompanying drawings in which the same is illustrated as embodied in a convenient and practical form, and in which— 70

Figure 1 is a plan view showing a portion of the automobile supporting frame with my improved cooling system mounted thereon; Fig. 2 an enlarged plan view of one of the 75 tubes of the radiator; Fig. 3 a cross sectional view of one of the radiator tubes; Fig. 4 an end elevational view looking from the right in Fig. 1; Fig. 5 a diagrammatic view showing the position of the partition in the radiator; and Fig. 6 a side elevational view looking upwardly with respect to Fig. 1. 80

The same reference characters are used to designate the same parts in the several figures of the drawings. 85

A' and A² indicate the side sills of the automobile frame which are united by the cross sill A preferably formed integral therewith.

B' and B² designate transverse trusses 90 united at their opposite ends to the side sills A' and A². The trusses intermediate of their ends are offset downwardly to allow sufficient space for the engine and co-operating mechanism. Reinforcing webs b' and b² 95 are preferably provided around the trusses to give them the requisite strength.

C' and C² indicate engine cylinders communicating at their inner ends with a crank casing C. c' and c² designate the valve casings. D indicates the crank shaft which is rotated in the usual manner by the reciprocations of the pistons in the cylinders through the connecting rods united to the 100

cranks. Such details are not shown in the drawings as they form no part of my invention and are well known in the art.

E' and E² designate water jackets surrounding the ends of the cylinders in which the explosions occur and through which a cooling fluid circulates.

F designates a conduit leading from a radiator H preferably mounted above the transverse beam A and communicating with the water jackets E' and E² at the tops thereof through the medium of the branch pipes f' and f².

G designates a second conduit communicating by means of branch pipes g' and g² with the water jacket E' and E² at the bottoms thereof and extending to and communicating with the radiator H. The radiator H preferably comprises a plurality of parallel tubes h having expanded hexagonal ends, the flat portions on the ends of adjoining tubes being directly connected and the diameters of the tubes between the ends being restricted by corrugations so as to form a space around and between the tubes for the circulation of the cooling fluid. By expanding the ends of the tubes forming the radiator and directly uniting them together the use of plates surrounding the ends of the tubes is unnecessary. Located within the radiator is a partition comprising a vertical portion K' extending in a plane between the ends of the conduits F and G and a horizontal portion K². The partition is shown in Fig. 5 as if composed of straight portions but when used in a radiator comprising tubes having directly united hexagonal ends the partitions are so deflected as to pass between the tubes.

The operation of my invention is as follows: The fluid in the water jackets E' and E² when heated by the explosions in the cylinders rises and passes through the branch pipes f' and f² into the conduit F from which it flows into the radiator, and circulates around the tubes H and is cooled by the air passing through the tubes. The liquid, after being cooled in the radiator, passes through the conduit G and branch pipes g' and g² into the water jackets.

As the branch pipes g' and g² of the return conduit G communicate with the water jackets at the lowest points thereof and as the branch conduits f' and f² communicate with the conduit F leading from the highest points in the water jackets, a circulation through the system is produced by reason of the liquid in the water jackets when heated, rising. The partitions in the radiator insure the hot water delivered to the radiator from the pipe F passing upwardly around the partitions, and when cooled, downwardly through the conduit G back to the water jackets.

From the foregoing description it will be

observed that I have invented an improved system for cooling the engine cylinder of an automobile, in which the circulation of the fluid through the system is induced without the use of pumps by the water when heated in the water jackets rising, and when cooled in the radiator, descending.

While I have described more or less precisely the details of construction, I do not wish to be understood as limiting myself thereto, as I contemplate changes in form, the proportion of parts, and the substitution of equivalents, as circumstances may suggest or render expedient, without departing from the spirit of my invention.

Having now fully described my invention, what I claim as new, and desire to secure by Letters Patent, is—

1. In a liquid cooling system for explosive engines, the combination with a water jacket around the cylinder, of a radiator, a partition within said radiator comprising a vertical portion extending upwardly from the bottom of the radiator and a horizontal portion extending from one side of the top of the vertical portion, a conduit leading from the top of the water jacket and communicating with the bottom of the radiator at one side of said partition, and a return conduit leading from the bottom of the radiator at the other side of said partition to and communicating with the bottom of the water jacket.

2. In a liquid cooling system for explosive engines, a combination with the water jacket around the cylinder of a radiator, a partition within said radiator comprising a vertical portion upwardly extending from the bottom of the radiator to a point above the top of the jacket and a horizontal portion extending from one side of the top of the vertical portion, a conduit leading from the top of the water jacket and communicating with the bottom of the radiator at one side of said partition, and a return conduit leading from the bottom of the radiator at the other side of said partition to and communicating with the bottom of the jacket.

3. In a liquid cooling system for automobile engines, a combination with a water jacket around the cylinder, a radiator supported at the front of an automobile and having a plurality of horizontal air tubes extending through the same around which the liquid circulates, a partition within said radiator extending upwardly from the bottom thereof to a point above the top of the water jacket, a substantially horizontal conduit leading from the top of the water jacket to the bottom of the radiator on one side of the partition, and an inclined conduit leading from the bottom of the radiator to the bottom of the water jacket on the other side of the partition.

4. In a liquid cooling system for auto-

mobile engines, the combination with a water jacket around the cylinder, of a radiator supported at the front of an automobile and having a plurality of horizontal air tubes extending through the same around which the liquid circulates, a partition within said radiator, a conduit leading from the top of the water jacket to the radiator on one side of the partition, and a second conduit extending from the bottom of the radiator to the bottom of the water jacket on the other side of the partition.

In testimony whereof, I sign this specification in the presence of two witnesses.

THOS. B. JEFFERY.
